SMOKING PIPE ATTACHMENT

Carl Bergman, Hopatcong, N. J.

Application March 22, 1937, Serial No. 132,286

3 Claims. (Cl. 131—176)

This invention relates to new and useful improvements in a smoking pipe attachment.

This invention has for an object the construction of an attachment as mentioned which is characterized by a perforated compound cap for engagement on the bowl of a pipe.

Still further the invention proposes the association of a flat perforated inner head mounted on a resiliently mounted stem extended from the 10 perforated compound cap by which the burned tobacco may be pressed down.

Still further the invention proposes the construction of an attachment as mentioned which is characterized by perforated inter-engaging 15 cap sections, one set within the other, and flexible tubes connecting the perforations of said sections in a manner to control the passage of air and fluids therethrough. This attachment is intended to be used in heavy rains and storms.

20 For further comprehension of the invention, and of the objects and advantages thereof, reference will be had to the following description and accompanying drawing, and to the appended claims in which the various novel features of the 25 invention are more particularly set forth.

In the accompanying drawing forming a material part of this disclosure:—

Fig. 1 is a perspective view of a smoking pipe attachment constructed according to this invention.

Fig. 2 is a sectional view taken on the line 2—2 of Fig. 1.

Fig. 3 is an elevational view looking in the direction of the arrows 3—3 of Fig. 2.

35 Fig. 4 is a similar view to Fig. 2 but illustrating a modified form of the invention.

The smoking pipe attachment, according to this invention, comprises a compound cap 10' for engagement upon the bowl of a pipe 11. This 40 compound cap consists of an outer cap section 10^c and an inner cap section 10^d. Each of these sections have perforated end wall portions and depending skirt portions. It is the skirt portions that engage one upon the other. The inner 45 cap 10^d has a projecting pin 16 which engages into a bayonet slot 17 formed in the skirt of the outer cap section. This bayonet slot 17 has a straight portion 17^a and a plurality of branch portions 17^b. It is possible to slightly turn the 50 outer cap 10^c to engage the pin 16 in any of the branches 17 and so hold the cap sections in various relative positions.

The top wall of the cap section 10^c is formed with perforations 12'. The top wall of the cap 55 section 10^d is formed with perforations 12''.

These perforations are staggered and are connected with each other by flexible tubes 19. When the sections 10^c and 10^d are adjusted to relative positions the tubes 19 will be moved. Normally, in the collapsed condition of the cap 5 sections the tubes 19 are loose and automatically assume the shape of an S-figure on its side. This shape acts as a trap to retain small quantities of water which may accidentally drip through certain of the top openings 12' during a rainstorm. 10 If in calm weather it is desired that more air be supplied to the pipe the outer section 10^c may be extended so that the tubes 19 are straight, as indicated by the dot and dash lines 19, and then the restriction to the passage of air through the 15 tubes is reduced.

The smoking pipe attachment also includes a stem 14 which is slidably mounted through the center of the compound cap 10'. This stem has a flat inner head 15 formed with perforations 16. 20 A spring 17 is coaxially mounted upon the stem 14 and acts between the inner face of the inner cap section 10^d and the head 15 for urging the head against the tobacco 18 within the pipe bowl. The outer end of the stem 14 has a small head 25 portion on 14^a by which it may be gripped and manually moved outwards.

In Fig. 4 the outer cap 10^c is spaced from the inner cap 10^d by a seat 10^b formed in the outer cap. Cotton, sponge, felt or other absorbent material 20 is placed in the hollow space 21 formed by the two caps. This absorbent material 20 may be saturated with flavoring substance to change the taste and fragrance of the smoke. The perforations 12' in the upper cap 10^c and perforations 12'' in the lower cap 10^d are in staggered 30 relation to permit a good mixture of the air drawn in by the smoker, with the flavoring substance in the absorbent material 20. 35

While I have illustrated and described the 40 preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. A smoking pipe attachment comprising perforated inter-engaging cap sections, one an inner section and the other an outer section, flexible tubes connecting the perforations of said sections, means for holding said sections relatively axially adjusted to slacken the flexible 50 55

tubes or to extend them, and said cap sections having skirt portions by which the attachment may be frictionally mounted on a pipe bowl.

2. A smoking pipe attachment comprising perforated inter-engaging cap sections, one an inner section and the other an outer section, means for spacing said sections, perforations in both cap sections, said cap sections having concentric flanges or skirt portions, the inner of said flanges being adapted to be frictionally mounted on a pipe bowl, absorbent material in the cavity between the spaced inter-engaging cap sections and flavoring substance within the said absorbent material, the perforations in the spaced inter-engaging cap sections being in staggered relation to permit the air drawn into the pipe by the smoker to mix with the flavoring substance in the absorbent material.

3. A smoking pipe attachment comprising an inner perforated section having a depending skirt portion which is adapted to frictionally engage over the top of a pipe bowl, an outer perforated section having a depending skirt portion which is adapted to engage over the top of said inner perforated section, flexible tubes connecting the perforations in said sections, and a shoulder arranged on the inner face of the skirt portion of said outer section which is adapted to engage the top face of said inner section to limit the engagement of said outer section on said inner section to a position in which said flexible tubes assume an S-shape which is adapted to act as a trap for drops of water which may pass through said perforation in said outer section during a rainstorm. 5 10 15
